UNITED STATES PATENT OFFICE.

FRED C. BROWN, OF SEATTLE, WASHINGTON.

PORTABLE SELF-HEATING HOT-WATER RADIATOR.

Application filed July 15, 1921. Serial No. 485,017.

To all whom it may concern:

Be it known that I, FRED C. BROWN, a citizen of the United States, residing at Seattle, in the county of King and State of Washington, have invented a new and useful Portable Self-Heating Hot-Water Radiator, of which the following is a specification.

This invention has reference to improvements in that type of portable radiators especially designed for heating rooms that have provision for holding a liquid fuel supply and are provided with thermostatic devices for regulating the feed of the fuel supply, and my said invention embodies, in a portable self-heating hot water radiator, certain features of construction and novel combination of parts, all of which will be fully stated in the following detailed description, pointed out in the appended claims and illustrated in the accompanying drawing, in which:

Figure 1 is a vertical longitudinal section of a portable hot water radiator constructed in accordance with my invention, the fuel control valve devices and the thermostatic means for actuating the said valve devices being diagrammatically indicated.

Figure 2 is an end elevation of my improved radiator, the heating chamber and the water heating elements being shown in dotted lines.

Figure 3 is a vertical section on a somewhat enlarged scale of the thermostatically controlled valve devices for controlling the fuel supply.

In carrying out my invention, the radiator is substantially the usual standard shape and it is composed of a series of units that include two opposite end units 1-1, which extend the full height of the radiator and whose lower ends terminate in bifurcations or foot members 10-10 to each of which is connected a caster 11-11 that provides for conveniently moving the radiator from place to place.

2-2 designates a series of intermediate radiator units, the upper ends of which are in alignment with the tops of the end units 1-1 and the said upper ends of the intermediate units join with one another through the lateral passages 20-20 in the solid or head portion 21 and which are in communication with the several intermediate radiator units, as shown.

It will be noticed by reference to Figure 1,

the lower ends of the intermediate radiator units merge with a solid base portion 22 and the said lower ends of the said units 2 connect with one another and with the opposite end units 1-1 by the lateral passages 30 in the base portion 22, as shown.

The intermediate radiator units 2 are of somewhat less height than the end units 1-1 whereby to provide ample space at the lower part of the radiator for a combustion or heating chamber 4 which, in the construction shown, is formed between a top section 40 that merges with vertical end portions 41 which in turn merge with a bottom portion 42 that joins with the vertical portions 41 and has extensions 43-43 that merge with the end units 1-1, as shown.

One of the end units 1, of my construction of radiator, is cast with a horizontal solid division 15, whereby an independent chamber 5 is provided at the upper end of the said unit, which chamber serves as a fuel holding compartment when the heating agent is a volatile fuel, as kerosene or gasoline, and which is delivered into the chamber through a feed aperture 50 in the top thereof and which is normally closed by a screw cap 16, as shown. The lower part of the said radiator unit 1 constitutes a water space which is in communication with the other legs or water holding units of the radiator, as is clearly shown in Figure 1, by reference to which it will be noticed the end unit 1, opposite the fuel holding unit, has a filling opening 17, at the top, through which the water is supplied to the radiator, which opening is normally closed by a cap 18, it being understood that when the radiator is filled with water, as indicated, the water, as it is heated, is caused to circulate through the radiator units in the direction indicated by the arrows α .

To observe the height of the water within the radiator units, a gauge glass 19 is located near the upper end of the water receiving unit 1, and at a suitable point along the said water unit 1, is mounted a thermostat 6, which is diagrammatically indicated, since the said thermostat may be of any well known construction, there being numerous types of thermostats suitable for use in this connection, and therefore a detailed description or illustration of the thermostatic device is deemed unnecessary.

60-61 designate electric circuit wires from the opposing contacts of the thermo-

stat 6 and they pass to a source of electrical energy, the cells or batteries 7, from which passes a circuit wire 62 that joins with the magnet 9. From the magnet 9 passes a line 5 63 back to the thermostat, as diagrammatically shown in Figure 3 of the drawings, which also illustrates the automatically operated valve control devices 8, presently explained in detail.

10 The heating element is a gas burner 65 of any approved type that is mounted on the bottom of the combustion chamber 4 and is suitably positioned for ejecting the flame against the heating coil of water circulating 15 pipes 10, the lowermost end 10^a of which extends through one wall 41 of the chamber 4 and taps into the lower or water space and adjacent end radiator unit 1. The uppermost end of the water heating pipe coil 20 passes through the other end 41 of the heating compartment 4 and connects with a vertically extended pipe 11 that discharges into the adjacent end unit 1 near the upper or water inlet end thereof, and as clearly shown 25 in the drawing.

12 designates a fuel conveying pipe which communicates with the fuel holding chamber 5 and passes down and connects with the automatically regulated valve control 8, 30 from which passes a pipe section 13 that communicates with and supplies the burner 65 which, in the practical development of my radiator is ignited by a simple pilot light of any suitable design that is kept 35 burning so long as the radiator is in use.

14 designates a handle located on the outside of the radiator base and which is applied to the stem of a valve 15 located in the feed pipe 13 that extends from the automatic valve control casing 80 to the burner 65 by which the fuel supply to the burner 65 may be cut off entirely when the radiator is not in use.

The thermostatic control device 8, hereinbefore referred to and illustrated in detail in Figure 3, comprises a suitable open top casing 80 that is located in the space between the radiator unit 1, in which is located the chamber 5 and the adjacent one of the 45 short or intermediate units 2.

Within the casing 80 is mounted a post 81, upon which is supported an armature lever 82 that is pivoted at 83 and is normally shifted to its released position by a spring 55 84 that connects with the post 81 and the lever 82.

An armature plate 85 is attached to one end of the lever 82 and it cooperates with the magnet 9 which is energized through 60 electrical connection with the batteries or cells 7.

The other end of the lever 82 carries a pendant latch member 86 that is adapted at times, as presently further stated, to engage 65 a collar 91 on a stem 92, that carries a valve

93 and which is normally moved to its fluid passage closing position by spring 94 that is suitably mounted within the valve casing 95 and engages the valve 93, as shown.

96 designates a pivoted lever detent that is 70 mounted on the valve casing and which drops under the the collar 91 on the valve stem and holds it up after it has been shifted to its uppermost position by thermostatic action until the magnet again responds to 75 the thermostat and becomes de-energized when the said latch device drops and catches under the member 96^a of the lever 96, which lever is pulled and caused to disengage the collar 91 and release the valve 93 when the 80 magnet again acts under thermostatic action, as the temperature of the water rises above the predetermined point and allows the valve 93 to instantly close under tension of its spring, at which position the parts re- 85 main until the magnet is further automatically energized, when the water cools down below the set temperature at which time the 90 operation of lifting the valve 93 is repeated, as before stated.

It is understood the thermostat operates to close the electric circuit from the cells to the magnet when it cools whereby to open the valves and it operates when heated to close the valve in a manner well known to 95 those familiar with thermostatic control devices used in connection with fuel regulating valve mechanisms.

From the foregoing description, taken in connection with the drawings, the complete 100 construction, the manner of its use and the advantages of my portable water radiator will be readily understood by those skilled in the art to which my invention relates.

While the specific arrangement of the 105 parts shown and described, presents a practical development of my improved self-heating portable radiator, it is to be understood that various details of construction and proportions of the parts may be varied 110 or modified to meet the different requirements in the practical application of my invention without departing from the spirit thereof, as is set out in the appended claims.

What I claim is:

1. A portable hot water heater comprising a radiator body that includes opposite end water legs or units and intermediate water legs or units that communicate with the end legs, a combustion chamber located below 120 the intermediate water legs and between the lower ends of the opposite end legs of the radiator body, a water heating pipe coil located in the combustion chamber, one end of which coil communicates with the lower 125 portion of one end leg while the other end of said coil is in communication with the upper portion of the other end leg, a burner within the combustion chamber for heating the water coil, a source of volatile fuel sup- 130

ply carried on the radiator body and a valve controlled feed pipe that connects the said fuel supply and the burner.

2. A portable heater comprising a radiator-like body that includes opposite end leg units, one of which has a volatile fuel holding compartment provided with a capped filling opening, a combustion chamber at the lower end of the said radiator-like body, a water heating pipe coil located within the said combustion chamber, one end of said coil being in communication with the lower portion of one of the end units of the radiator body, and the other end of said coil

being in communication with the upper end 15 of the other end unit of the said body, a liquid fuel burner located in the said chamber for heating the pipe coil, a valved feed pipe that connects the liquid fuel compartment of the radiator body with the burner 20 and thermostatic means mounted on the radiator cooperative with the valve in the fuel feed pipe and adapted for automatically controlling the adjustment of the valve in accordance with the varying temperatures 25 of the water in the radiator body.

FRED C. BROWN.
